ELECTRIC VACUUM SWEEPER NOZZLE
ATTACHMENT

Clifford E. Hain, Omaha, Nebr.

Application March 23, 1936, Serial No. 70,439

3 Claims. (Cl. 15—13)

My invention has to do particularly with the art of electric vacuum sweeper nozzle attachments and with vacuum sweeper attachments generally.

5 It is an important object of my invention to provide a vacuum sweeper nozzle attachment that will brush and beat a rug or the like simultaneously.

Another object of my invention is to provide 10 a device of this character wherein the brushes will work the nap of a rug or the like with a whisk broom effect.

Another object of my invention is to provide 15 a device of this character wherein beaters are provided on each side of the brush in parallel relation thereto.

Another object of my invention is to provide 20 a device of this character wherein the beaters extend substantially the entire length of the nozzle intake opening.

Another object of my invention is to provide 25 a device of this character wherein the wear on a rug or the like due to the beating and brushing thereof is reduced to a minimum.

A further object is to provide a device of this 30 character wherein a rapid, vibratory beating action is imparted to the beater bars and brushes which move with a rocking or oscillating action.

A still further object is to provide a device of 35 this character wherein the operation thereof is smooth and efficient.

Other objects of my invention will appear in the following detailed description taken in connection with the accompanying drawing wherein:

35 Figure 1 is a side elevation of the device in partial section taken on line 1—1 of Figure 2.

Figure 2 is a plan view of the device with the nozzle broken away along line 2—2 of Figure 1 40 to show the attachment in operative association therein.

Figure 3 is a partial section taken on line 3—3 of Figure 2.

Figure 4 is a partial section taken on line 4—4 of Figure 1.

45 Figure 5 is a diagrammatic view of the device to show the oscillating or rocking action of the beater bars.

Referring more particularly to the drawing, which illustrates a preferred embodiment of the 50 invention, reference numeral 10 indicates generally the nozzle of a vacuum sweeper within which is secured a frame comprising end plates 11 secured together in spaced relation by a longitudinally extending rod 12. The plates 11 fit against 55 the inner surface of the side walls 13 of the

nozzle 10 and the attachment is swivelly secured in the nozzle by screws 14 through the plates 11 and threadably received in the end or side walls 13 of the nozzle. On the inner side of each end plate 11 is a bearing support 16 secured to the 5 respective plates 11 by rivets 17. Each bearing support is provided with a notch 18 closed at the rear side of the attachment and in said notches are received elongated lugs 19 of bearing races 20. Within the bearings are operatively received the respective ends of a longitudinally extending rotatable shaft 21, said ends being in operative association with balls 22 in the bearing race.

At the longitudinal center of the shaft 21 is 15 a pulley 23 secured thereto by a set screw 24. The pulley is connected with the sweeper motor, not shown, by a belt 25 of the usual slightly elastic type, said belt tending to pull the attachment upwardly and inwardly of the nozzle opening, but 20 same is limited in its pull by flanges 15.

Adjacent each end of the shaft 21 is an eccentric 26 secured thereon by set screws 27, said eccentrics being adapted to operate in unison with each other.

25 A stud 28 is riveted to each plate 11 and support 16, said studs extending longitudinally inwardly from the inner sides of the respective plates 16 and below the shaft 21. Each stud 28 is provided with a shoulder from which projects 30 a longitudinal extension, threaded adjacent its free end. On each stud extension is oscillatingly received an oscillating or rocking member 29 secured thereon by nuts 30 threadably received on the threaded ends of the respective stud extensions. Each oscillating member 29 is provided 35 with a notch 31 at its upper end operatively receiving the respective eccentrics 26.

Each oscillating member 29 is also notched at the bottom to receive the beater which comprises 40 two parallel, laterally spaced, longitudinally extending beater bars 32 connected together adjacent their respective ends by integral, substantially U-shaped portions 33 shaped to be received in the lower notches of the respective members 29, said portions 33 being secured in the lower notches of members 29 by screws 34.

Below the shaft 21 and on each side of the pulley 23 is a longitudinally extending brush support 35 in which the upper ends of the brush bristles 36 are secured, said bristles extending 50 downwardly between the beater bars 32 with the lower ends of said bristles on substantially the same plane as a plane across the lower surfaces 55

of said beater bars, said brushes being substantially parallel with the beater bars.

The brush support 35 is spaced below the shaft 21 and is offset at 37 to permit free movement of the pulley 23. At each end of the support 35 same is turned downwardly at 38 and outwardly at 39 and secured to the respective oscillating members by screws 40.

It should be noted that the beater bars operate substantially within the intake opening and extending substantially the entire length thereof.

Upon rotation of shaft 21 the eccentrics 26 rotate within the notches 31 causing the oscillating members 29 to oscillate or rock on the extensions of the studs 38 as shown by the arrows 41 in Fig. 5. The rocking of the oscillating members 29 causes the beater bars 32 to also rock or oscillate in an effective beating action as shown by arrows 42 in Figure 5. As the brushes are secured in fixed relation to the beater bars and oscillate therewith brushing and beating is provided by my invention. A rapid succession of blows by the beater bars and short sweeps by the brushes occur which are less destructive to the fibers of a rug or the like than the frictional agitation of rotary agitators and brushes.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

Having thus described my invention what I claim is:

40. 1. A vacuum sweeper attachment adapted to be secured in the nozzle of a vacuum sweeper having an intake opening therein, a frame, said frame including end plates, means for removably attaching a bearing to each end plate, a shaft 45 rotatably mounted in said bearings, an eccentric on each end of the shaft adjacent the respective bearings, an oscillatable member adja-

cent each end plate, said members having notches in which are operatively received the respective eccentrics, said oscillatable members being operatively mounted on their respective end plates, a pair of laterally spaced, longitudinally extending substantially parallel beater bars attached adjacent their ends to the respective oscillatable members, and brush means secured in fixed relation relative to the beater bars, said brush means being received longitudinally between said bars.

2. A vacuum sweeper attachment adapted to be secured in the nozzle of a vacuum sweeper having an intake opening therein, a frame, said frame including end plates, means for removably attaching a bearing to each end plate, a shaft rotatably mounted in said bearings, a pulley on said shaft adjacent the longitudinal center thereof, an eccentric on each end of the shaft adjacent the respective bearings, an oscillatable member adjacent each end plate, said members having notches in which are operatively received the respective eccentrics, said oscillatable members being operatively mounted on their respective end plates, a pair of laterally spaced, longitudinally extending substantially parallel beater bars attached adjacent their ends to the respective oscillatable members, and brush means secured in fixed relation relative to the beater bars, the brush means extending longitudinally between said bars, said means having an offset portion adapted to receive said pulley to permit free movement thereof.

3. A vacuum sweeper attachment adapted to be secured in the nozzle of a vacuum sweeper, a frame including end plates, a shaft rotatably associated with said end plates, an eccentric on each end of the shaft adjacent the end plates, an oscillatable member rockingly mounted on each end plate and having notches within which the respective eccentrics are operably received, a pair of substantially parallel beater bars attached to said oscillatable members, said bars being laterally spaced apart, and brush means secured in parallel and fixed relation to said beater bars.

CLIFFORD E. HAIN.
